UNITED STATES PATENT OFFICE.

CHARLES SCOTT AND CHARLES T. SCHOEN, OF PHILADELPHIA, PA.

CAR-SPRING.

SPECIFICATION forming part of Letters Patent No. 251,739, dated January 3, 1882.

Application filed March 17, 1881. (No model.)

To all whom it may concern:

Be it known that we, CHARLES SCOTT and CHARLES T. SCHOEN, citizens of the United States, residing at the city of Philadelphia, in the State of Pennsylvania, have jointly invented certain new and useful Improvements in Car-Springs; and we do hereby declare the following to be a full, clear, and exact description of the same, reference being had to the accompanying drawing, forming part of this specification.

Our invention has for its object to produce spiral springs of such construction that four of the same will be sufficient for the bolster-springs of a freight-car.

Heretofore in constructing spirals to form bolster-springs for freight-cars it has been found necessary, owing to the construction adopted, to make each spring consist of a group or nest of such spirals; nor has it been found practicable until our invention to substitute for such group or nest a single spiral. To be practicable, a spring for the purpose suggested must have great bearing capacity and due range of motion, without too great stiffness, within the vertical limits where the spring is located—namely, between the spring-plank and bolster. It has heretofore been found necessary, as above intimated, to make such spring, if spiral, to consist of a group or nest. We have discovered, however, that with a bar of certain proportions coiled on its edge on a mandrel of regulated size we can produce a spiral of such construction that a single one will form a complete spring having a bearing capacity and range of motion equal to the group or nest heretofore employed, being at the same time softer or more easy in motion, requiring considerably less metal, and being much less liable to breakage than such group or nest.

Our invention accordingly consists of a bearing or bolster spring made from a bar whose thickness is not greater than half its width, the diameter of the spring being equal to or greater than its height. The configuration of the bar in cross section is not an essential feature of our invention. Such bar may accordingly be of any configuration coming within the terms that its thickness shall not be greater than half its width, or, what is the same thing, that it shall be at least twice as wide as it is

thick. Hence the bar may be a rectangular oblong—that is, of even thickness throughout, with parallel sides and edges. It may also be ovaloid or ovaliform, having a greater thickness at its middle or between its edges than at either edge; and this form we prefer, though, as already stated, our invention is not limited to any particular configuration so long as the same comes within the relative proportions assigned as to width and thickness. The length of the bar and the mandrel on which it is coiled must be such that when the spiral is completed its diameter will be greater than its height, the spiral thus having a relatively greater diameter than any heretofore employed for the purpose for which this is intended. One such spiral will produce a complete bolster or bearing spring for a freight-car, four such spirals being all that is required for a freight-car.

From the foregoing it follows that the diameter of the spiral must have due relation to the width of the bar, and that the width of the bar must be proportional to the mandrel-hole in the spring. For example, if the spiral be, say, eight inches in diameter, the bar should be, say, two and three-eighths inches wide, and its thickness at its thickest part be, say, one and one-eighth inch, the mandrel-hole being, say, three and one-quarter inches. The width of the bar is thus about thirty per cent. of the diameter of the spiral and about three-fourths of the diameter of the mandrel-hole. These or approximate proportions being preserved, it follows that a single spiral of our improved construction will have the same height as one of a nest or group as heretofore constructed, while its width, bearing-surface, or area will be equal to the aggregate of the several spirals composing a group or nest. The relative proportions of the height of such spiral to its diameter, and of the width of its bar to such diameter and to the diameter of the spring-hole, are thus wholly different from those of spirals in groups or nests, and distinguish our spring very characteristically therefrom.

The figure shows a sectional view of a spring conformable to the description above set forth.

The advantages of this improvement are, first, a saving of metal, as a single spiral of construction described requires less metal than the group or nest heretofore employed; second,

greater softness or ease of action; third, very greatly reduced liability to breakage, as there is very much less danger of breaking a single spiral of a given capacity than there is of 5 breaking spirals composing a group or nest forming a spring of the same capacity.

What we claim as our invention is—

A single-coil bearing or bolster spring consisting of a bar coiled on its edge, the width 10 of said bar being substantially twice its thickness and about three-fourths the diameter of

the mandrel-hole, the diameter of the spiral being equal to or greater than its height, substantially as shown and described.

In testimony that we claim the foregoing we 15 have hereunto set our hands this 2d day of February, 1881.

CHARLES SCOTT.

CHARLES T. SCHOEN.
